UNITED STATES PATENT OFFICE.

EDWIN H. HILL, OF WORCESTER, MASSACHUSETTS.

METHOD OF AND MECHANISM FOR STRAIGHTENING METAL BANDS.

SPECIFICATION forming part of Letters Patent No. 290,231, dated December 18, 1883.

Application filed May 28, 1883. (No model.)

To all whom it may concern:

Be it known that I, EDWIN H. HILL, a citizen of the United States, residing at Worcester, in the county of Worcester and State of Massachusetts, have invented certain new and useful Improvements in the Method of and Mechanism for Straightening Flat Metal Bands, Wires, and Rods; and I do hereby declare the following to be a description of my said invention, sufficiently full, clear, and exact to enable others skilled in the art to which it appertains to make and use the same, reference being had to the accompanying drawings, which form a part of this specification.

15 In the manufacture of flat metal bands, wire, and rods, the metal becomes curved and crooked edgewise in the rolling or flattening operation, and much time, labor, and expense is required in bringing it into a straight condition suitable 20 for market and use, and much care has to be exercised to avoid twisting or warping the band or wire while straightening it laterally.

The object of my present invention is to provide means whereby flat metal bands, wires, 25 or metal rods can be straightened in an expeditious, convenient, and economic manner; also, to provide a practical and efficient mechanism for straightening flat metal bands, wires, and rods by continuous operation. These objects 30 I attain by mechanism the nature of which is more fully explained in the following description, the particular subject-matter claimed being hereinafter definitely specified.

In the drawings, Figure 1 is a side view of 35 mechanism for straightening flat metal bands, wires, and rods, illustrating the nature of my invention. Fig. 2 is a top plan view of the same. Fig. 3 is a vertical transverse sectional view, and Fig. 4 is a bottom view of one of 40 the guide-plates.

In my improved apparatus for straightening, the flat metal bands, wires, or rods are passed forward through suitable guides or supports which bear against the metal at intervals along 45 its edges, and which also confine it flatwise sufficiently close to prevent any twisting action. Then, while it is thus confined and supported, it is subjected to a series of sharp, quick blows, dealt upon its edges by a simultaneously- 50 operating series of hammers operating in rapid succession from opposite directions, and regu-

lated in their force of impact according to the degree of power required or best adapted for the particular size of wire or class of material under treatment.

The best method now known to me for practically applying my invention to use in the operation of straightening flat bands or wire is by a mechanism consisting of a series of spring-actuated hammers or strikers arranged 55 at intervals, and alternating at opposite sides of the wire with intervening guides or anvil-blocks, and provided with suitable shafts and cams, or devices for successively operating the several hammers for delivering blows upon 60 the edges of the wire, and means for regulating the force of the blows, such mechanism being arranged substantially as hereinafter 65 illustrated and explained.

In the references, A denotes the table or bed- 70 plate, provided with lateral slots, in which operate the hammers or straighteners B, and having arranged on its upper surface in longitudinal direction the guides or supporters C, which together form a course or runway for 75 the wire D as it passes from one end of the table to the other. The lower edge of the guide-blocks C are provided with recesses or grooves e, of proper form to fit over and confine the wire flatwise and to sustain it at 80 intervals edgewise, the grooves of the guide-block being made, as indicated in Fig. 4, with parallel ends at c' c', while the central part of the groove e, opposite the striker B, is hollowed or rounded out, as at d, to permit the wire to 85 give way or bend with the blows of the straighteners or hammers B. The hammers B are in the present instance mounted on reciprocating rods E, that work through guides on the under side of the bed-plate A, and are pro- 90 vided with suitable springs, F, for forcing them forward against the edges of the wire. The strikers and their rods are moved outward in opposition to the springs by the cams or wipers G on the shafts H, mounted in suitable 95 bearings beneath the bed A, and which shafts may be geared together, as at I, and be operated by a crank or by a belt on the pulley J, or by any other suitable means, as convenient. The cams G press outward the hammers 100 B, and the springs F send them inward against the wire with a sharp, quick blow, when the

end *b* of the striker falls from the cam. The outer ends of the rods *E* are provided with nuts *K*, which strike upon elastic washers *L*, arranged at the sides of the bed, and which serve to stop or cushion the blows of the strikers against the wire *D*. By turning the nuts *K* on the rods *E*, the force of the blows can be varied and regulated to give the effect required. The wire *D* can be drawn through the guides by feed-rolls *M*, arranged at the position shown, or by any suitable feeding mechanism, as desired.

In the present instance four hammers, *B*, and a similar number of guide-blocks, *C*, are shown; but any number desired may be employed without departure from the nature of my invention. The guides *C* serve as anvils for the hammers *B*, which latter are preferably arranged alternating with and opposite to the guides, as shown, and the guide-blocks are firmly secured to the bed-plate by bolts.

The several hammers may be arranged to operate one at a time and to follow their strokes in rapid succession, so as to equalize the power required for driving the shafts *H*; and the number of strokes in relation to the speed at which the wire is fed forward can be so varied or proportioned that the entire length of the rod will be subjected to the hammer action along its edges, so that it comes out from the machine straight and uniform.

If desired, the guides *C* may be made adjustable to receive bands or wires of different widths.

What I claim as of my invention, and desire to secure by Letters Patent, is—

1. In a machine for straightening flat metal bands or wire, a series of automatically-operated hammers or strikers adapted to deliver simultaneous blows upon the opposite edges of the band or wire at intervals of its length as it is fed forward through the machine.

2. The combination of a series of hammers adapted to deliver blows upon the opposite edges of the band or wire simultaneously at intervals of its length, and mechanism for operating the same, and a series of guides adapted to sustain the wire laterally at either side of the hammers, while permitting its bending action in front of said hammers.

3. The combination of a series of hammers adapted to deliver blows upon the wire or band, and simultaneously acting at intervals of its length, the mechanism for operating the

same, and a series of guides adapted to support the wire laterally at either side of said hammers, and to confine the wire flatwise and against twisting action.

4. The combination of a series of hammers or strikers alternately located at opposite sides of the feed-face, and adapted to deliver blows upon the edge of the band or wire at intervals of its length, and mechanism for operating the same, a series of guides to sustain and confine the wire or band, and adjusting devices for regulating the force of the hammer-strokes.

5. The combination, with the wire-confining guides, of a series of hammers or strikers operated by springs and cams, for delivering blows upon the wire or band, substantially as set forth.

6. The combination of the hammers or strikers mounted on reciprocating rods guided and supported on the bed-plate, the actuating-springs arranged on said rods for forcing said hammers inward against the wire, and the revolving shafts provided with cams for moving said hammers outward and compressing said springs, as set forth.

7. The elastic stop-cushions *L* and the adjusting-nuts *K*, in combination with the rods *E*, the hammers *B*, the springs *F*, and table *A*, in the manner shown, for arresting and regulating the force of the hammer-strokes.

8. In a machine for straightening flat metal bands or wires, the combination, with the supporting-bed *A* and mechanism for continuously feeding forward the band or wire, of guides *C*, that confine the wire flatwise upon said bed and support it laterally at intervals of its length, and a striker mechanism for imparting laterally-straightening force at positions intermediate to the bearing-points of the edge-supporting guides, said parts being arranged and operating as set forth.

9. The guide-plate *C*, provided with the guiding groove or recess *c*, having parallel bearing ends *c' c'*, and hollowed at the center, as at *d*, in combination with the bed *A* and hammers *B*, for the purpose set forth.

Witness my hand this 25th day of May, A. D. 1883.

EDWIN H. HILL.
